UNITED STATES PATENT OFFICE.

RUDOLPH WINNIKES, OF BERLIN, GERMANY.

COMBINED CARBONIC-ACID RECEIVER AND PRESSURE-REGULATING MECHANISM.

SPECIFICATION forming part of Letters Patent No. 613,810, dated November 8, 1898.

Application filed August 16, 1897. Serial No. 648,450. (No model.)

To all whom it may concern:

Be it known that I, RUDOLPH WINNIKES, a subject of the German Emperor, residing at Berlin, Germany, have invented a certain new and useful Improved Combined Carbonic-Acid Receiver and Pressure-Regulating Mechanism, of which the following is a full, clear, and exact description.

The present invention consists of a combined carbonic-acid receiver and pressure-regulating valve for use in retailing liquors, such as beer and the like.

The invention consists in the details of construction hereinafter set forth, and particularly pointed out in the claims.

In order to render the present specification more easily intelligible, reference is had to the accompanying drawings, in which similar letters of reference denote similar parts throughout the several views.

Figure 1 is a central vertical section through the device; Fig. 2, a top plan of the same; Fig. 3, a horizontal section on line A B of Fig. 1; Fig. 4, a similar section on line C D of Fig. 1; Fig. 5, a section on line E F of Fig. 1; Fig. 6, a section on line G H, Fig. 1; and Fig. 7, a side elevation, partly in section, of a modified form of the device.

Referring to Figs. 1 to 6, the device consists of a bell or receiver, which is divided by means of a horizontal partition into an upper or carbonic-acid-containing receiver A and a lower chamber B, which contains the pressure-regulating mechanism. The partition separating the chambers is provided with a strengthening-rib y, in which is mounted the tubular downward extension e, forming a channel through which the carbonic acid may pass to the lower chamber B. The lower end of the tube e is covered or loosely inclosed in an inverted thimble-piece g, having therein a plate h, adapted to close against the lower open end of the said tube. This thimble rests on the free end of a lever i, pivoted in a bifurcated bearing-piece f, screw-threaded into the strengthening part y of the partition. The opposite end of the said lever is pivoted to the lugs n' of a nozzle having a boring n², said nozzle being suitably fixed in a membrane k, mounted at the bottom of the chamber B and partitioning this chamber off from the lower chamber C. The lower chamber C is provided

with a tubular downwardly-extending mouth-piece having a lateral opening v and being interiorly screw-threaded to receive a nut p, 55 having upwardly and downwardly extending tubular extensions and being provided with lateral orifices w, Fig. 4, into which a tool may be inserted through the opening v, so that the position of the said nut in the throat-piece 60 may be varied. The upper surface of the nut forms the bearing-surface for the spring o, which bears against a metal washer on the membrane and has the tendency to push said membrane upwardly. Thus if the position 65 of the nut p is altered the tension with which the spring o bears against the membrane may be regulated. The downwardly-extending end of the nozzle, having boring n², is provided with a flexible tubular extension q, consisting 70 of two parts, which are held together by means of an inserted glass tube q', the lower end of said flexible tube opening into an upper chamber formed in the housing of the cock D.

The device is screwed into the bung, plunger-siphon, or tap, which is in connection with the cask. Its operation will be obvious. As soon as liquor is drawn off the pressure underneath the membrane will decrease and carbonic acid will pass from the receiver A to the 80 chamber B through the outlet e and from chamber B through the opening n² to the interior of the cask, the constant pressure in the cask being regulated according to the adjustment of the spring o.

The dimensions of the glass and flexible tubes are so chosen that in case of excessive pressure the latter will slip off the glass tube and thus form a reliable safety-valve.

The top of the receiver A is provided with 90 a valve device through which carbonic acid may be supplied to the said receiver. At the upper part of the housing A is provided a nozzle having interior and exterior threads, into the former of which a plug r is screwed, 95 while the latter is covered by means of a nut a. The lower part of the plug r is hollowed out to receive a second plug d, having therethrough an orifice t, said plug forming with its upper surface a seat for a free-lying valve-plate c, having formed in its under surface channels s s, Fig. 6. The main plug r is provided with a central vertical channel u and with two depressions z z, by means of which

the said plug may be screwed into the neck of the receiver. When carbonic acid is to be supplied to the receiver A, the nut *a* is unscrewed and the mouthpiece of the carbonic-acid flask screwed onto the neck of the receiver. The carbonic acid will flow through the channel *u* onto the valve-plate *c* underneath the same through the channels *s* into the receiver A, and when the flask is detached from the neck or nozzle of the receiver the valve-plate *c* will be closed by the interior pressure against the plug *r*, thus preventing the escape of the carbonic acid from the receiver.

15 In the modification shown at Fig. 7 instead of the orifice *n*² a laterally-formed channel *a'* is provided. The device is otherwise the same as that previously described.

20 The cock *D* may be employed to close the apparatus when it is shifted from one cask to the other or when it is charged and not in use.

I claim as my invention—

1. The combination of a carbonic-acid receiver and a chamber as specified and partition between the two, a tubular outlet *e* from the receiver to the chamber, having inverted thimble-piece to inclose same loosely, a lever *i* and means for suspending the same pivotally from the partition-wall between the receiver and chamber, pivotal connection between the end of said lever and a downwardly-extending nozzle, a membrane closing the bottom of said chamber and means for attaching said nozzle to the membrane, a chamber *C* below said membrane having throat-piece with lateral opening *v* an adjustable

nut in said throat-piece accessible through said opening, a spring arranged between said nut and a plate on the membrane, a flexible tube connection from the membrane-nozzle, 40 said tube connection being in two parts, a glass tube to connect said flexible tube parts a cock to close said throat-piece and means for securing the whole to the cask or the like substantially as described.

2. The combination of a carbonic-acid receiver, a valve-chamber thereunder and a partition between the two, a membrane underneath and closing said chamber, a tubular downwardly-extending outlet to said partition 45 an inverted thimble-piece to loosely inclose said outlet a lever device in connection with the membrane to operate said thimble, a chamber below the membrane having therein an adjustable membrane-spring, a cock below said spring and an outlet from the valve-chamber to said cock, a carbonic-acid inlet to the receiver consisting of a plug *r* having mounted therein a second plug *d* an orifice *t* in said second plug a valve-plate thereover 50 having channels *s* in its under surface, and an orifice above said valve-plate through the plug *r* and a cap-nut *a* to inclose the whole substantially as described.

In testimony whereof I have signed my 55 name to this specification in the presence of two subscribing witnesses.

RUDOLPH WINNIKES.
